VEHICULAR TRAILER BED

Edmund S. Grilley and James R. Nolan, Fort Worth, Tex., assignors to Hobbs Manufacturing Company, Fort Worth, Tex., a corporation of Texas

Application September 6, 1949, Serial No. 4,866

Term of patent 14 years

(Cl. D14—3)

To all whom it may concern:

Be it known that we, Edmund S. Grilley and James R. Nolan, citizens of the United States of America, residing at Fort Worth, State of Texas, have invented a new, original, and ornamental Design for a Vehicular Trailer Bed, of which the following is a specification, reference being had to the accompanying drawing, forming a part hereof.

Fig. 1 is a perspective view of a vehicular trailer bed, showing our new design.

Fig. 2 is a rear end elevational view of the bed.
Fig. 3 is a top plan view of the rear portion of the bed,

Fig. 4 is an underside plan view of the rear portion of the bed,

Fig. 5 is a side elevational view of the rear end bed portion,

Fig. 6 is a side elevational view of the vehicular trailer bed, and

Fig. 7 is a top plan view of the bed.

The characteristic features of our design reside in the portions shown by means of full lines in the drawing.

We claim:

The ornamental design for a vehicular trailer bed, as shown and described.

EDMUND S. GRILLEY.
JAMES R. NOLAN.
